FLASHOVER INDICATOR

Harold L. Rorden, William E. Scarborough, and
Merwin B. Elton, Portland, Oreg.

Application July 10, 1950, Serial No. 172,994

2 Claims. (Cl. 340—253)

(Granted under Title 35, U. S. Code (1952),
sec. 266)

1

The invention described herein may be manufactured and used by or for the Government of the United States for governmental purposes without the payment to us of any royalty thereon in accordance with the provisions of the act of March 3, 1883, (22 Stat. 625), as amended by the act of April 30, 1928, (45 Stat. 467, 35 U. S. C., 1946 ed. sec. 45).

This invention is concerned with electric power transmission lines. In particular, it is concerned with means for indicating when a tower or pole supporting transmission line conductors has been subjected to flashover.

There are other flashover indicators in the prior art, some of which resemble the present flashover indicator in some aspects of operation. Our invention is concerned with improvements over other similar devices, partly in mechanical structure and partly in method of operation.

This flashover indicator is of the type in which operation is accomplished with the release of a signaling device by the ignition of a small charge of explosive powder. The ignition occurs when a high-voltage flashover occurs on the line structure to which the indicator is attached.

A principal object of our present invention is the production of a flashover indicator that is simple and inexpensive, and which will operate reliably under severe service conditions.

Another object is to produce a flashover indicator that will operate reliably when infested with vermin such as cocoon-producing larva. Still another object is to provide electrical connections for the flashover indicator which will provide reliable operation on either steel or wood towers of transmission lines.

What constitutes our present invention is set forth in the following specification with reference to the drawing and succinctly defined in the appended claims.

In the drawing,

Figure 1 is an elevation showing a front view of a preferred embodiment of our invention mounted with appropriate electrical connections on a wood transmission line pole.

Figure 2 is a partly sectional elevation of the same indicator as shown in Figure 1, but from the back, whereas Figure 1 is a front view.

Figure 3 is a partly sectional view of the same indicator as shown in Figure 2, showing the indicator in position prior to operation; whereas Figure 2 is illustrative of the indicator after operation.

Figure 4 is a partly sectional elevation looking at the left-hand edge in reference to Figure 1.

2

Figure 5 is an illustration of the mounting of the indicator on a steel tower together with specially applicable electrical connections.

In reference to Figure 1, a flash indicator case 1, made of Bakelite or similar material is supported on a wood pole 2 which supports transmission conductors in the usual way. The flash indicator case 1 is supported on pole 2 by an adjustable conducting strap 3 secured by a bolt 4 which hold also a bracket 5, a flashover rod 6 and an adjusting device 7. Elements 5, 6 and 7 are adopted from the system of lightning grounding on which an application for patent, No. 583,483, has been filed by Harold L. Rorden.

On pole 2, below the indicator 1, there is a loop of wire 8 which is connected by a wire 9 to a terminal 11 on the side of the indicator. A connection 12, shown in Figures 2, 3 and 4 on the back of case 1, connects strap 3 to the interior of the indicator.

Hinged at one side of case 1, near the bottom, there is an indicating closure 14, referred to as an indicating drop, of the shape of one-fourth of a circle. On the face 15 of drop 14, a reflecting surface is provided to make the drop easily seen at night when illuminated by a spot light. The configuration of drop 14 is such that when the indicator is set prior to an indication, the laterally extending bottom of case 1 is closed by the bottom of indicator 14 as shown in the section of Figures 3 and 4.

A conducting wire spring 16 is provided to connect strap 12 to a clip 17 inside the indicator for electrical operation and also to provide a mechanical force on drop 14 tending to force the drop open.

Clip 17 holds one end of spring 16 to provide a mechanical rest for the spring pressure as well as electrical contact therewith. Clip 17, as usually used in the practical construction of our invention, is an ordinary Fahnstock clip. This form of clip provides a convenient attachment of conductors.

Inside case 1, on the side with terminal 11, a spring latch 18 formed from a resilient metal piece projecting outside case 1 and formed into a hook or loop 19 is connected to terminal 11 by the strip 21. The strip 21 is made with spring pressure toward the inside of the case.

An explosive link 22, comprising an outer shell, a small explosive charge 23 and two conducting wire terminals 24 and 25, is held securely at terminal 25 by clip 17 at one end. The other end, terminal 24, is supported by spring latch 18, as shown in Figure 3. Link 22, held in clip 17 and

supported by latch 18, holds drop 14 up in the closed position against the force of spring 16.

Drop 14 is released into the indicating position shown in Figure 2 when link 22 explodes after ignition by any electric impulse of sufficient voltage to jump across the space containing the charge 23 between the inner ends of terminals 24 and 25. In setting the indicator for use, link 22 is inserted in clip 17 and catch 18 is pulled back by tension applied by the attendant on loop 19. Drop 14 is then pushed up to the closed position and the terminal 24 secured in position above clip 18. When ignited by an electric spark, the charge 23 explodes, bursting link 22 and permitting drop 14 to fall to the position shown in Figure 2. In Figure 2, the remainder of link 22 including the terminal 25 and the adherent remains of the shell of the link 22 is shown held by clip 17 in the dropped position after operation.

Referring again to Figure 1, the electrical voltage that explodes link 22 is impressed thereon between strap 3 and wire loop 8. This voltage is conducted by strap 12 from strap 3 to spring 16 through clip 17 and terminal 25 to the charge 23, and through terminal 24, clip 18, connection 21, terminal 11 and wire 9 to wire 8. This installation is characteristic of wood-pole lines in which flashover is to rod 6, usually from the line conductor, through the indicator and down the pole from wire loop 8.

A different way of getting voltage for ignition is used on steel towers as shown in Figure 5. The indicator 1 is mounted on a steel member 26 of the tower, one leg 27 of which is indicated. Wire conductors 9 and 28, analogous to conductor 9 shown in Figure 1, is carried down the tower, for example, down a diagonal member 29. Conductors 9 and 28 are insulated from the tower by insulators 31 or by other conventional means.

Conductor 28 is connected to a ground rod 32 situated near the tower leg footing at which members 27 and 29 are terminated. Figure 5 does not show the footing details, the drawing extending only to the ground surface 33. The footings usually are several feet deep and of similar lateral dimensions. The ground rod 32 is placed only sufficiently far from the footing to develop a difference of potential between the ground rod and the footing sufficient to ignite the explosive charge 23. This potential difference is attained, under average fault conditions, when the separation between the ground rod and tower footing is about one foot. It has been found that much greater spacings sometimes pro-

duce difference of potentials sufficient to damage the indicator by flashing over between terminal 11 and other parts inside the case 1. The exact spacing under practical conditions needs to be determined by experience.

We claim:

1. In a flashover indicator the combination of an insulating rectangular case, a hinged bottom in said case with a sector attached to said bottom, arranged to be concealed in said case when said bottom is in the closed position, and visible below said case when said bottom is in the open position, a spring positioned in said case to apply opening pressure to said bottom, a spring pressure clip attached to said bottom and to one end of said spring, a conducting strap on the back of said case for external electrical connection to which the other end of said spring is also connected, a terminal on one side of said case and, connected therewith, a spring catch inside said case, and a flashover by-pass which includes an electrically ignited explosive link held at one end by said spring pressure clip and retained at the other end by said spring catch, said link holding said bottom in the closed position normally and releasing said bottom to the open position when ignited.

2. In a flashover indicator the combination of an insulating case with an indicating bottom drop and closure provided with a reflecting surface, a supporting pivot within said case, said indicating bottom drop and closure being eccentrically mounted on said pivot, an explosive drop supporting link in said case, a spring yieldingly forcing said drop against said link, and a flashover circuit which includes said link, whereby a surge of current in said circuit serves to ignite the explosive of said link permitting gravity and the resilient action of said spring to eject said indicating bottom drop from said case.
